TRANSFER MECHANISM

Francis A. Hosack, Rye, N. Y.

Application May 22, 1936, Serial No. 81,198

10 Claims. (Cl. 235—133)

My invention relates to calculating machines and particularly to that class in which totalling and listing operations are carried on in conjunction with the calculating functions. A principal object of the invention is to provide transfer mechanism adapted for use in association with devices for controlling the actuator bars to prevent the printing of zeros to the left of the registering values in adding, subtracting and totalling operations, such as are disclosed in my prior Patents No. 1,823,859, issued September 15, 1931, and No. 1,938,907, issued December 12, 1933.

A second object of the invention is to provide for the release of the actuator bars for orders to the left of a value entered on the keyboard, after printing has taken place, to enable movement of these bars for effecting required transfer operations.

Another object is to provide individual restoring frames which permit a limited step motion of the actuator bars independently of the operating shaft thereby enabling transfers to be effected when the actuator bars, on their way back to normal positions, are in coacting relation with the register pinions.

A further object is to provide mechanism for bringing the register pinions into and out of coacting relationship with the actuator bars at the proper times.

Other objects and advantages of the invention will be apparent upon consideration of the following description and appended claims when read in conjunction with the appended drawings in which:

Fig. 1 is a sectional elevation at the left of the column of keys of highest denomination and shows the various parts in non-operated position;

Fig. 2 is a sectional view on the line 2—2 of Fig. 1 illustrating the manner in which the actuator bars cooperate with the key stems, and also shows the side frames of the machine;

Fig. 3 is a sectional view on the line 3—3 of Fig. 1 and shows the bar locks for the actuator bars;

Fig. 4 is a sectional view on the line 4—4 of Fig. 1 and shows the zero locks for the actuator bars;

Fig. 5 is a fragmentary sectional elevation at the right of the column of keys of lowest denomination;

Fig. 6 is an enlarged view of part of Fig. 1 and shows certain of the mechanism for controlling and operating the actuator bars;

Fig. 7 is a sectional view on line 7—7 of Fig. 6;

Figs. 8 to 12 are detail views showing various cooperative relations of a transfer lever associated with one numeral pinion and the actuator bar for the numeral pinion of next higher order;

Fig. 13 is a fragmentary view of the mechanism for restoring the pinion frames;

Fig. 14 is a side view of a portion of the device including the bars for unmeshing the accumulator gear frames from the segmental gears, the parts being shown in the initial position of the 10 actuating handle;

Fig. 15 is a side view of the construction disclosed in Fig. 14 with the parts in the positions assumed when the actuating handle is in its forward position;

Fig. 16 is a sectional view, partly broken away, taken on line 16—16 of Fig. 1;

Fig. 17 is a perspective view of a detail of the device showing the key stem locks and the mechanism for operating the key stem locks;

Fig. 18 is a greatly enlarged side view of a portion of the device disclosed in Fig. 1; and

Fig. 19 is a perspective view of a portion of an accumulator gear frame and the slide associated therewith.

This application is a continuation in part of my copending application Serial No. 701,283, filed December 7, 1933, now abandoned, which is a continuation in part of application Serial No. 337,287, filed February 4, 1929, now abandoned, and 30 337,284 was a continuation in part of Serial No. 49,565 now Patent No. 1,823,859.

In Fig. 1, I have shown a longitudinal section of a keyboard in which the respective keys 1 to 9, inclusive, of the various columns making up the 35 keyboard are supported and guided in horizontally spaced plates 10, 11 and 12. Each key is held in its normal position by a spring 27 acting between plate 11 and a seat 28. The seat 28 is a flange projecting from the key which bears 40 against the upper end of the spring 27. The lower end of the spring 27 is supported on the bar 11. When the key is depressed, the spring 27 is compressed. Actuator bars 13, of which there

is one for each column of keys, pass through cut-out portions 32 adjacent the lower ends of the key stems as shown in Fig. 2. The keys in each column are disposed when in assembled relation so that the cutout portions 32 in all the key stems of a column are in alignment for guiding and supporting the actuator bars. The portions of the actuator bars which pass through the aligned slots in the key stems are provided adjacent their top and bottom edges with laterally projecting stops 14, 15, 16 and 17, as indicated in Fig. 1. 45 50 55

These stops are adapted when brought into proper assembly with the slotted key stems of a column to be engageable with certain projecting portions of the key stems to limit the movement of the actuator bars.

Each stop on an actuator is adapted to cooperate with a projecting portion 35 or 36 (Fig. 2) of a certain key of the column with which the bar is associated so that when the key is depressed and the bar is moved the stop engages the projecting portion of the key to limit the operation of a printing segment 84 by the actuator bar to a number of increments of movement corresponding to the value of the depressed key. The arrangement of the projecting portions on the various key stems and their relation to the stops on the actuator bar is more fully described in my prior Patent No. 1,823,859.

At one side of each column of key stems is a key stem lock 29 having trunnions 29a journaled in the plates 30 and 31, so that it can swing into and out of engagement with laterally positioned depressions or notches 29b and 29c (Fig. 2), formed in the key stems adjacent their upper ends. The key stem lock 29 engages the notches 29b when all the keys are in raised position and is adapted to engage the notches 29c of the keys to hold them in depressed position.

Near the forward end of each actuator bar 13 is a slot 38 for receiving a bar lock for the actuator bar and a slot 39 for receiving a zero lock for the actuator bar as shown in Fig. 5. Referring to Fig. 3, the bar locks consist of a series of members 40, one for each actuator bar, pivotally mounted on one side of the plate 30 at 44. When no keys are depressed the bar locks depend perpendicularly, as indicated by the position of 40, with solid portions of their lower ends in the slots 38 of the actuator bars and consequently all the actuator bars are locked against movement. Each bar lock is provided at its lower end with a slot 48. Laterally projecting members such as pins 52, are carried by the bar locks and are engageable by arms 56, secured to the keystem lock trunnions 29a which extend through the plates 30. The arm 56, for example, moves with the related keystem lock 29 on depression of a key in that column and acts against the pin 58 to move the bar lock 40 so that slot 49 registers with actuator bar 13 for that column to permit its movement.

The lower ends of all the bar locks are in abutment so that when a key in any column to the left of the first column is depressed the unlocking movement of the actuator bar lock in that column causes the locks for all columns to the right to move to unlocking position, while the bar locks to the left remain in locking position. A single spring 60 associated with the right-hand bar lock 40 biases all the bar locks into locking relation with the slots 38 of the actuator bars. A bell crank 61 pivoted on plate 30 engages the bar lock 40 at the extreme left to effect simultaneous release of all the bar locks, as will be described hereinafter.

The zero locks for the actuator bars comprise members 64 (Fig. 4), pivoted on the other side of the plate 30 at 66. The zero locks are biased by individual springs 72 so that their lower ends rest in the slots 39 of the respective actuator bars. The slot 39 in each actuator bar is wider, as shown in Fig. 5, than the zero lock by an amount equal to the distance the actuator bar must travel to bring the printing segment 84, to be presently described, into position to print a zero.

The zero locks normally prevent the actuator bars 13 moving more than enough to bring the printing segments to zero position. Adjacent their lower ends the zero locks are provided with projections such as pins 80, adapted to be acted upon by arms 76, carried by the keystem locks 29 of the respective columns so that when a key is depressed in a column the zero lock for the corresponding actuator bar 13 is moved out of the slot 39 in the bar permitting the bar to be moved to index the printing segment 84 in accordance with the value of the depressed key.

The operation of the zero locks differs from the operation of the bar locks in that the zero locks move independently of each other and normally remain locked except when they are individually released by operation of the key stem locks 29 as a result of depression of a key in the corresponding columns.

The bar locks and zero locks, when released, are held out of locking relation position by the arms 56, or 76, carried by the key stem locks acting against the pins 52, or 80. This is because when a key is depressed the key stem lock 29 is moved out of the notch 29b in the key stem and engages the notch 29c which is of lesser depth so that the key stem lock 29 does not return to its normal position until released from locking relation with the key stem.

A suitably guided bar 73 operable by a bell crank 73a pivoted to plate 30 and having slots 73b, into which the pins 80, etc., carried by the zero locks extend, is provided for simultaneously releasing all the zero locks, as will be described hereinafter.

Below actuator bars 13 and the main shaft 151 which has an operating handle, not shown, is the restoring frame shaft 103. The restoring frame shaft has adjacent each end thereof an arm 151b connected by links 151c and 151d to shaft 151. The shaft 103 is operable in one direction by the main shaft 151 and in the opposite direction by springs 151e connected to pins 151f on arms 151b and to the frame of the machine at 151g. Mounted on the shaft 103 are the restoring levers 104, one for each actuator bar, having at their upper ends studs 105 which control the actuator bars 13. These restoring levers are keyed to the shaft by means of the keys 103a fitting in keyways 106 which are enlarged as shown in Fig. 6, so that the restoring levers 104 and the shaft 103 are capable of limited relative movement for a purpose to appear hereafter. Passing around each lever 104 is a spring 107 the ends of which are secured to shaft 103 so that the spring acts as a resilient coupling between the shaft 103 and the restoring lever 104 within the limits of the keyway 106 and normally urges the levers clockwise as viewed in Fig. 6.

The actuator bars which are horizontally guided in the plates 11 and 12 and vertically guided in the key stems, as above described, have lugs 13d projecting through elongated slots in the plate 12. The lugs are connected to one end of springs 13c for moving the actuator bars rearwardly, the other ends of the springs being connected to the plate at 13b. At their rearward ends the actuator bars 13 have racks 37 engaging toothed portions 85 of the printing segments 84, preferably mounted on a common shaft 84a with proper provision for retaining them in alignment with the actuator bars. The printing segments 84 are illustrated as having printing portions 86 on their edges, the printing portions 86, as shown, being provided with eleven divi-

sions, one blank and the other comprising type from 0 to 9. A platen 88 and a ribbon 87 act in conjunction with the type on the segments 84 to effect printing.

The platen 88 has a shaft 89 supported adjacent each end of frames 88a pivoted at 88b and connected by links 88c to arms 88d carried by the main shaft 151. In order that the platen and ribbon may be moved against and away from the type faces at the proper times the links 88c have a pin and slot connection to frames 88a, so that the frames are moved by the main shaft at the end of the forward stroke of the operating handle. Springs 88f are provided to move the platen 88 away from segments 84. Shoulders 88r formed on slots 88e in links 88c are adapted to engage studs 88h to move the platen frames 88a to effect printing. The links 88c have cams 88s engaging a bail 88t for raising the links 88c so that the platen 88 may be moved away from type faces 86 by springs 88f after printing has taken place, the studs 88h moving in the extensions 88u of the slots.

The bell crank 61, Fig. 3, for releasing the bar locks 40 is connected by a link 61a to one end of a lever 61b, Figs. 1 and 6, pivotally mounted on plate 12. The other end of lever 61b extends adjacent restoring frame shaft 103 which is provided with a cam or stud 103c. Stud 103c is positioned for engaging and rocking lever 61b to cause release of the bar locks after printing has taken place, to permit the previously locked actuator bars to be moved one increment rearwardly by springs 13c. This increment of rearward movement is provided to insure that all bars are positioned for effecting such transfer operations as may be necessary as will appear later.

Numeral wheel pinions 90, each associated with a cam 91 so that a pinion and cam move together, are mounted on a shaft 94, which is supported by a frame 92 adjacent each end. The frames 92 are pivoted on a shaft 93 and springs 92a, connected between the shafts 84a and 94, are provided to bias the pinions 90 into engagement with the toothed portions 85 of the segments 84.

A latch 92b pivoted at 92c is provided for each frame 92 and is biased into engagement therewith by a spring 92d for normally holding the numeral pinions 90 out of engagement with the toothed portions 85. As best shown in Fig. 15, studs 105 of two of the restoring levers 104, those adjacent the pinion frame 92, extend laterally from their levers 104 and are adapted to engage and release the latches 92b to permit engagement of the numeral wheel pinions 90 and the toothed portions 85 of segments 84, as will be described later.

A bar 138, slidably mounted on pins 137 projecting through slots therein, is adapted for engagement with the frame 92. A strong spring 139 connected at one end to one of the pins 137 and at the other end to a pin 139a on the bar 138 urges the latter toward the frame 92, but the bar is normally held retracted by a latch 140 pivoted at 140a and urged into engagement with a notch 140b. The latch 140 lies in the path of cam 136.

Pivoted at 141a is a normally vertically-extending lever 141, the upper end 141b of which is beveled and is urged into engagement by spring 141c with the pin 151h connecting links 151c and 151d (Figs. 1, 13, 14 and 15). Pivoted on pin 141d to the lower end of lever 141 is latch

141e, the beveled tip of which lies in the path of the pin 138a on bar 138. A spring 141f holds the latch against abutment 141g on lever 141, so that the latch is normally aligned with lever 141 and cannot move further in a clockwise direction because of the abutment 141g but is free to move in a counterclockwise direction.

Pivotedly mounted on a shaft 101a supported by an extension 100 of each frame 92 are transfer levers 101, one for each numeral wheel pinion except that of the highest order (Figs. 16 and 18). One end 101b of each lever 101 engages the corresponding cam 91 so that when a numeral pinion passes from 9 to 0 position, the raised portion 91a of the cam causes the lower end 101c of the lever to be moved out of the path of movement of a stop 102 adjacent the rack 37 on the actuator bar 13 associated with the numeral pinion of the next higher order. The levers 101 are releasably retained in either position by means of friction elements, such as for example, spring washers 101f (Figs. 16 and 18).

Forward of each numeral wheel pinion 90 is a pinion lock 95 pivotally mounted on a shaft 96 and having teeth adapted to mesh with the pinion 90 to retain the latter in its operated position.

A subtracting lever 98b projecting through the casing is secured to shaft 98a and is connected to a link 98d. The shaft 98a extends transversely of the machine and has fixed thereto adjacent its other end an arm 98f connected to a link 98g. As shown in Figs. 1, 18 and 19, the links 98d have slots engaging studs on extensions of levers 98, pivotally mounted adjacent each side of the frame 92 (Fig. 16). Springs 98c bias the levers 98 to the position shown in Fig. 1. The levers 98 are pivotally supported on the main frame by means of a shaft 98k. As shown in Figs. 16, 18 and 19 the levers 98 support bails 101d and 101e, the bail 101d acting on upward movement of levers 98 to move the end 101b of each adding transfer lever 101 from contact with the cams 91 and the ends 101c out of engaging relation with the stops 102 on the actuator bars 13. The bail 101e is normally positioned in the path of movement of the ends 101c of the transfer levers 101 for restoring the latter after they have been tripped to effect additive transfers. Springs 98i bias the levers 98b and the parts connected thereto to normal position.

In order that the adding pinions may be meshed with the toothed portions 85 of the printing segments 84 at the proper time for effecting subtraction, the lever 98b is operatively connected to slides 62 (Figs. 18 and 19), one of which is mounted on each of the frames 92 and suitably guided for vertical movement. The links 98d and 98g operable by shaft 98a are connected to bell cranks 98p, each pivotally mounted on a frame 92. The bell cranks 98p each have a slot 98r receiving a floating connecting stud 62d, also extending into a slot 62e in the corresponding slide 62. The connections 62d, 98r, permit movement of the frames 92 without actuating links 98d and 98g, and the connections 62d, 62e permit movement of the slides without moving the links, whereas the rocking of bell cranks 98p by the subtracting lever 98b through the links acts through slots 98r, studs 62d, and slots 62e to raise the slides. As shown in Figs. 1 and 18, adjacent its lower end each slide carries a stud 62b adapted to engage the arm of a bell crank 75

63a pivoted on the frame of the machine at 63b. The other arm 63e of each bell crank pivotally supports a latch tripping member 92f adapted on rocking of bell crank 63 to engage a pin 92g on the pinion frame latch 92b to move the latter about its pivot out of latching relation with the associated pinion frame 92. A spring 63d is connected to trip 92f and pivot 63b for restoring trip 92f and bell crank 63. Each frame 10 92 carries a stud 92h for also controlling the corresponding latch 92f, as will be described.

In order that no printing can occur in the totalling operations as to columns to the left of the amount so to be printed, I provide a cipher lock 134 for each actuator bar. Cipher lock levers 121 are pivoted on the shaft 101a. At its upper end each cipher lock lever 121 has a cam surface 124a normally engaging the raised portion 91a of the corresponding cam 91 and at its lower end a bearing surface 126. Below each actuator bar 13 is a cipher lock 134 pivotally supported on a shaft 129 which is slidably mounted in guides on the side frames of the machine, as shown in Fig. 16. The ends of the shaft 129 20 are received in vertically disposed grooves in the blocks 129e on the main frame of the device, which allows vertical movement of the shaft 129. Each cipher lock 134 is held against the bearing surface 126 of the corresponding cipher lock lever 25 121 by a tension spring 131 while the superior spring 132 tends to force the cam surface at the upper end of lever 121 against the pinion cam 91. The bottom edges of the actuator bars are cut away to form shoulders 133 adapted to engage the upper ends of the cipher locks 134 when the latter are raised. Pivotaly mounted on a shaft extending across the pinion frames 92 are a plurality of latches 135, one for each cipher lock, adapted to pass through slots in the cipher locks 40 134 to hold the locks firmly when they are raised and engage the shoulders 133 of the actuator bars.

Each cipher lock is arranged to operate the next adjacent cipher lock to the right in the series to insure that, when any one of the pinions 90 with its cam 91 has moved from zero position, permitting the cipher lock lever 124 to move off the raised portion 91a of the cam and to carry with it its cipher lock 134, those cipher locks to the right of said cipher lock will be carried rearwardly therewith as is shown and described in my Patent No. 1,938,907. In the position assumed by the cipher locks so moved about the shaft 129 their upper ends are displaced counterclockwise as viewed in Fig. 18 from the path of movement of the shoulders 133 on the bars 13 when all the cipher locks are moved upwardly and the latches 135 cannot engage with the slots of the respective cipher locks 134 during totalling operations.

The total key 74 and subtotal key 75 are guided in the plates 10 and 11. A key stem lock 74a, similar to locks 29 for the numerical keys is provided for engaging notches in the keys 74 and 65 75 to maintain the latter in depressed position until the lock is released, whereupon the keys may be raised by their springs 75b and 74b.

The total key has a lug 75g positioned above a lug 75c on the subtotal key, so that depression 70 of the total key also effects depression of the subtotal key. The subtotal key is connected to one arm of a bell crank 75d fixed to a shaft 75e. The other arm of bell crank 75d is connected by a link 75f to an arm 129b on the shaft 129 75 on which the cipher locks 134 are pivotally mount-

ed, as shown in Figs. 1 and 18. The shaft 75² extends transversely of the machine and adjacent its other end carries an arm 75g (Fig. 5) connected by a link 75h to another arm 129b also mounted on the shaft 129 (Fig. 16). The arrangement is such that depression of the subtotal key, or depression of the total key acting through the lugs 74g and 75c on the total and subtotal keys, causes a toggle movement of the links 75f and 75h forwardly. This causes the shaft 129 to move upwardly in its guides under the influence of the arms 129b and this upward movement of the shaft 129 carrying the cipher locks 134 causes the ends of the cipher locks 134 to move into position to be engaged by the shoulders 133 on the actuator bars.

The links 75f and 75h are connected to bell cranks 75k, as shown in Figs. 1, 16 and 18, one of which is pivotally mounted adjacent each frame 92. This connection permits only substantially linear movement of the links 75f and 75h. Forward movement of the links 75f and 75h therefore causes a counterclockwise rotation of the levers 129b and an upward movement of their upper ends. The upward movement of the upper ends of levers 129b causes the shaft 129 to move upward in the guides in blocks 129e. The bell cranks 75k are also connected to members 75l each having at their upper ends a seat 75n resting beneath one of the levers 98 (Figs. 1, 18 and 19). The members 75l are adapted on operation of the subtotal key, either directly or from the total key, to raise the members 75n and turn levers 98. This movement of levers 98 is only enough to cause movement of the ends 101c of transfer levers 101 sufficiently to disengage them from the stops 102 on actuator bars 13 and thereby permit movement of frames 92 to cause engagement of pinions 90 with the toothed parts of segments 84. However, this movement of transfer levers 101 is not great enough to move the ends 101b of the levers from the paths of the raised portions 91a of cams 91 and thus the transfer levers remain effective to serve as zero stops for the pinions 90. The links 75f and 75h are also provided with studs 75i for engaging the arms 63a of the bell cranks 63 to cause release of the frame latches 92b.

The lug 75c on subtotal key 75 is adapted to 50 engage and operate the bell crank 73a associated with the zero locks 64, etc. (Fig. 4). Key 75 also has a lug 75a for operating bell crank 61 which pertains to the bar locks 40, etc. (Fig. 3). Thus, operation of subtotal key 75, directly or 55 from total key 74, effects simultaneous release of the bar locks and zero locks for all the actuator bars.

Other elements which would be embodied in a complete machine to operate in conjunction with the subtracting lever 98b, and total and subtotal keys 74, 75 for registering and listing functions are disclosed in my Patent No. 1,938,907 but are omitted herein to simplify the present disclosure. 60

Referring to Figs. 2, 5 and 17, a bar 29d having 65 a slot 29e for each key stem lock 29 is provided for releasing the key stem locks from the key stems, so that the depressed keys may be re- stored by their springs 27, and for moving the arms 56, etc., and 76, etc., associated with the 70 pins on the bar locks and zero locks, respectively, to permit locks which have been released to be restored to locking position by the springs associated therewith. The bar 29d is biased to normal position by a spring 29f so that the notches 75

29e are normally disposed to permit movement of any key stem lock on depression of a key in the corresponding column.

Bar 29d is connected to one end of a lever 29h pivotally mounted in the plate 11. Lever 29h carries at its other end a pivotally mounted dog 29k, extending into the path of a movement of a cam 13a having an inclined forward edge on the actuator bar 13 of lowest denomination. The dog 29k carries a pin 29n adapted to limit the movement of the dog about its pivot on lever 29h, the arrangement being such that on rearward movement of the actuator bar 13 cam 13a engages and pivots the dog without operating lever 29h while on forward movement of the actuator bar cam 13a engages and because of its inclined edge cams the dog 29k laterally away from bar 13, thereby operating lever 29h and moving the bar 29d to the right (Figs. 2 and 17) for causing release of the key stem locks 29. This arrangement may be duplicated for as many actuator bars as deemed desirable. In any event the above described mechanism is provided for the actuator bar associated with the column of lowest denomination since this bar moves, at least one step in each direction, whenever a key is depressed in any column. The key stem locks for the total and subtotal keys are operatively associated with the locks 29 for the numeral keys so that they are released in conjunction with release of the latter as disclosed in my Patent No. 1,938,907.

The operation is as follows:

When the key in any column is depressed the key stem lock 29 for that column is moved out of engagement with the notch 29b of the key stem. The arm 56, for example, moves with its key stem lock and acts on pin 52 on the bar lock 40 moving the slot 48 into alignment with the actuator bar 13 to permit its movement. The release of the bar lock in any column also effects the release of the bar locks for all of the columns to the right since the actuated bar lock is in abutment with the adjacent bar locks. This is illustrated in Fig. 3, where depression of a key in the fifth column from the right has caused the key stem lock 29 of that column to move arm 56 releasing bar lock 40 for the actuator bar 13 of the fifth column. The bar lock 40 has caused the release of the bar locks for the actuator bars of all columns to the right. It should be noted that the bar locks 40 for the columns to the left of the fifth column remain in locking position. It should also be noted that unless a key is depressed in a particular column the related key stem lock 29 is not released, the pin 52 on the bar lock moving therewith away from the arm 56, carried by the key stem lock. This is illustrated in the first, third and fourth columns, while the position of the arm 56 indicates that a key has been depressed in the second column also.

The arm 76 also moves with the key stem lock 29 for the fifth column and acts on the pin 80 on the zero lock 64 for that column moving zero lock 64 out of the notch 39 in the actuator bar 13. As the key is depressed, the key stem portion between notches 29b and 29c acts on key stem locks 29 to cause the bar locks and zero locks to be moved slightly beyond released position by arms 56 and 76. Springs 60 and 72 act on the right bar lock and the released zero locks to move arms 56 and 76, through studs 52 and 80 to move the key stem locks sufficiently to engage notches 29c to hold the keys in depressed position.

When the operating handle secured to the main shaft 151 is moved forwardly, the restoring lever shaft 103 is moved counterclockwise (Fig. 1), carrying the restoring levers 104 and permitting the actuator bar springs 13c to move the actuator bars rearwardly. The actuator bars for columns in which keys have been depressed, having their bar and zero locks released, move rearwardly until stops, such as 14, on these actuator bars engage projections 35 of the key stems for limiting the movement of the printing segments by racks 37 to an amount corresponding to the value of the depressed keys.

The combination of the bar locks and the zero locks insures the printing of zeros to the right of any key which is depressed and inhibits the movement of any actuator bars to the left of that key. This is for the reason that any bar lock which is thrown out carries all of its right hand neighbors with it to permit the actuator bars for these columns to move at least enough to index the printing segments in zero printing position while the zero locks normally release individually and only on depression of keys in the corresponding columns. The actuator bars for columns to the right of a column in which a key has been depressed move rearwardly a single step to move the printing segments 84 for these columns to zero printing position, the movement of these bars being limited by their zero locks. This is illustrated in Fig. 9, the bar 13 having moved rearwardly one increment positioning this bar stop 102 one step away from the end 101c of the transfer lever 101 of next lower order, in which position the bar is held by its zero lock 64. Bars 13 for columns in which keys have been depressed have their zero locks released and move rearwardly beyond the position indicated in Fig. 9 a number of increments corresponding to the value of the key depressed, as in Fig. 11 ready for a return movement in the direction of the arrow. The actuator bars to the left of the amount entered on the keys are held by their bar locks in the position shown in Fig. 8 and do not follow the movement of the restoring levers 104.

As the restoring lever shaft 103 is rotated from the position shown in Fig. 14, the cams 136 turn therewith, releasing latch 140, and at the same time, links 151c and 151d move to the left so that their pivot pin 151h turns lever 141 in a counterclockwise direction as seen in Fig. 1. Lever 141 engages pin 138a and advances bar 138 to the right until latch 140 engages the notch 140b to hold the bar in retracted position against the tension of spring 139. The latch 141e on lever 141 then swings clear of pin 138a, though its upper end 141b remains held by pin 151h, as shown in Figs. 1 and 15. Subsequent return of links 151c and 151d and their pin 151h allows spring 141c to restore lever 141 to vertical position, latch 141e snapping over the pin 138a as it passes.

Release of frame 92 by the bar 138 in its aforementioned movement to the right, permits numeral pinions 90 to be moved by spring 92a from engagement with pinion locks 95 and into engagement with the toothed portions 85 of printing segments 84. However, pinions 90 do not engage the toothed portions 85 during the rearward movement of the actuator bars in addition, inasmuch as the pinion frames are still held by the latches 92b.

After the segments 84 have been indexed in printing position the studs 105 of restoring levers 75

104 move rearwardly therewith away from the actuator bars 18 which are held by the key stem stops, bar locks, or zero locks, as the case may be. The levers 104 are thus rotated by the springs 107 clockwise relatively to the shaft 103 as far as is permitted by the lost motion connection formed by key 103a and the enlarged keyway 106.

The platen frames 88a are brought forwardly by the main shaft 151 through the arms 88d and links 88c and subsequently to the termination of the rearward movement of the actuator bars the platen 88 and the ribbon 87 engage the type portions 86 of the segments 84 which have been adjusted to the printing line in accordance with 15 the movement of the actuator bars. After links 88c have moved the platen against the type faces the forward movement of the links 88c causes the cams 88s to engage the bail 88t raising the links so that the offset parts of slots 88e register with the studs 88h on the platen frames. Springs 88f act on the platen frames to move the platen away from the type faces as studs 88h move in the parts 88u of the slots 88e.

After the printing has been effected the studs 25 103c moving with restoring frame shaft 103 move lever 61b about the pivot 12a and acting through link 61a turn bell crank 61 (Figs. 3 and 6). This movement of bell crank 61 moves all the non-released bar locks 40 about their pivots to released position with the slots at lower ends of the locks in alignment with the actuator bars 18. The previously locked actuator bars, those to the left of the fifth column under the conditions assumed above, are then moved rearwardly by their 30 springs 18c a single increment to the position shown in Fig. 9, the movement of the bars being limited by the engagement of the rearward end of slots 39 with the zero locks, this arrangement insuring that all bars are movable forwardly at 35 least the one increment that may be required to effect additive transfers. No additive transfer will be produced unless a lever 101 is rocked by engagement with a cam 91a. With the lever 101 in the position shown in Fig. 18 the lug 101c is disposed in the path of forward movement of the 40 next higher actuator bar 18. This disposition of the lug 101c prevents the actuator bar 18 from moving beyond a position corresponding to zero position of the segmental gears 85 or printing segments 86. Return movement of the actuator bars engaged by the lugs 101c to blank position is prevented except when the accumulator gears 90 have been unmeshed from the segmental gears 85.

55 At the end of the forward stroke of the operating handle the studs 105 on the restoring lever adjacent pinion frames 92 contact the latches 92b (Fig. 15), disengaging the latter from the pinion frames, which are then moved rearwardly by the springs 92a so that the pinions 90 move from engagement with the pinion locks 95 and into engagement with the toothed portions 85 of the printing segments. As the pinions 90 move into engagement with the toothed portions 85, the pins 92h on the pinion frames engage the latch trip member 92f, moving the latter out of the path of movement of the pins 92g on the latches 92h, so that the latches may subsequently reengage the pinion frames, as will appear later.

70 As the pinion frames 92 swing rearwardly the adding transfer levers 101 are carried therewith so that the ends 101c of the transfer levers which are supported on the frames 92 are moved from the position of Fig. 9 into contact with the stops 75 102 as in Fig. 10, on all actuator bars which have

not been released by their zero locks, all stops 102 having been moved rearwardly at least one increment during the movement of bars 13, as described above.

When the operating handle is released the 5 main springs 151e, which were tensioned during the rearward movement of the restoring levers 104, turn restoring frame shaft 103 carrying levers 104 therewith to engage the actuator bars for moving them forwardly. The studs 105 on the 10 restoring levers adjacent the pinion frames 92 move from engagement with the latches 92b and the springs 92d move these latches into position for subsequently locking the pinion frames.

When studs 105 reengage the actuator bars the 15 latter are moved forwardly, the springs 107 are placed under tension and the racks 97 rotate the printing segments 84 and the toothed portions 85 thereof, being engaged with the pinions 90, operate the pinions in accordance with the numerals entered on the keyboard. As the actuator bars move forwardly the stops 102 engage the ends 101c of transfer levers 101 which hold the actuator bars one step from normal or blank position. The levers 104 which engage these bars 25 also stop while the shaft 103 continues to rotate clockwise, the lost motion connection 103a and 106 allowing this action to take place. Fig. 11 shows a bar, which was fully released for entering a numeral, moving forwardly while operating the 30 numerals pinions.

In the event that any numeral pinion 90 has been rotated from the nine position through the zero position during forward movement of the actuator bar 18, the raised portion 91a of the cam 35 91 associated with that pinion rocks the corresponding transfer lever 101 rearwardly, moving the end 101c of the transfer lever out of the path of the stop 102 on the bar 18 of next higher order as shown in Fig. 12. This bar having been 40 positioned rearwardly at least from blank to zero position or one step in addition to the number of steps produced by depressing the key, is restored to normal by its lever 104 and thus effects the transfer. For example, if a key of the value of 45 five is depressed, the corresponding actuator bar 18 can move rearwardly six steps. Bars whose transfer levers have not been tripped are held by the engagement of 101c with their stops 102 one step from normal or blank position. As the 50 restoring lever shaft 103 continues its clockwise movement the levers 104 related to these bars which are restrained by the engagement of 101c with bar stop 102 are held from full forward movement and springs 107 are additionally tensioned, storing power therein. In the event a delayed transfer from a lower order to a higher order causes tripping of the transfer lever related to one of the actuator bars of still higher order, the restoring lever 104 for this last actuator bar is moved by its spring 107 while the pinions 90 are engaged with the toothed portions 85, so that the actuator bars are restored successively to normal position, Fig. 12, and the corresponding numeral pinions are each rotated successively an additional step to effect additive transfers prior to release of the latch 140 by the cam 136. The lost motion connections 103a and 106 between the restoring shaft 103 and the restoring levers 104 allow the shaft to continue to 60 rotate and provide a sufficient interval of time for a complete succession of transfers to take place before the latch 140 is tripped.

At the end of the rearward movement of the operating handle and after any additive transfer 75

has been effected by the power stored in spring 107, the cams 136 on shaft 103 engage pawls 140 to disengage them from the notches 140b in the corresponding bars 138 to release them for sudden movement to the left, as seen in Fig. 13, by their tensioned springs 139. The bars 138 accordingly strike the corresponding frames 92, rocking the latter to move pinions 90 from engagement with the toothed portions 85 and into engagement with the pinion locks 95. As the pinion frames are moved rearwardly the transfer levers 101 are carried therewith and all actuator bars which have been held from normal position, as in Fig. 10, are moved forwardly by the springs 107 of the restoring levers to the position shown in Fig. 8, as the stops 102 on the actuator bars follow the movement of the ends 101c of the transfer levers. The ends 101c of the transfer levers 101 which have been tripped, Fig. 12, to effect a transfer, engage the bail 101e carried by the levers 98 and are restored to normal position in abutment with the stops 102 on the actuator bars of next higher order.

As the pinions 90 are demeshed the frames 92 and latches 92b move clockwise and studs 92h move with frames 92 to permit the springs 63d to position trip members 92f above the pins 92g on the latches (Fig. 1). Latches 92b, biased by springs 92d, engage frames 92 and lock the pinions 90 in their non-meshing position.

On rearward movement of the actuator bars to the right in Fig. 5 to index the printing segments the cams 13a (Fig. 17) thereon engage the dogs 29k pivoting the latter about the pivots 29i without effecting movement of the levers 29h and bar 29d. However, as the actuator bars 13 which have cams 13a move forwardly to normal position each cam engages the related dog 29k. As pins 29n prevent pivotal movement of dogs 29k by cams 13a on forward movement of the bars 13 the dogs are cammed sideways away from the bars and act to rock the lever 29h about pivot 29i. As a lever 29h is turned about its pivot it moves the bar 29d so that the shoulders of the notches 29e engage the key stem locks 29 moving the latter from engagement with the notches 29c of the key stems. The springs 27 associated with the depressed keys return the latter to normal position.

As the cam 13a moves beyond and from engagement with the dog 29k the bar 29d is returned to normal position by the spring 29f. On return of the bar 29d the shoulders of the notches 29e move away from the key stem locks 29. The spring 60 associated with the bar lock of lowest denomination, acts to pivot all the released bar locks so that the slots 48 are moved from registration with the actuator bars and the solid portions of the bar locks are moved into the notches 38 of the actuator bars to lock the latter in normal position. The individual springs 72 associated with the released zero locks move the zero locks so that their ends are positioned in the notches 39 in the actuator bars. The key stem locks again engage the key stem notches 29b as the arms 56, and 76, are moved by the pins on the bar locks and zero locks.

In the event that the bar locks and zero locks are released before all of the actuator bars have moved to normal position, the springs associated with these locks bias them against the actuator bars so that when the actuator bars have moved to position the notches 38 and 39 in alignment with the bar locks and zero locks the latter

will enter the notches to lock the bars in normal position.

When subtraction is performed it is to be understood that the operating sequence is somewhat different from that in addition, as described above; for example, the numeral pinions 90 are in engaging relation with the toothed portions 85 of the printing segments during the rearward movement of the actuator bars and are in disengaged relation during the forward movement of the actuator bars.

When a number is to be subtracted the subtracting lever 98b is moved to and held in operative position. It is to be understood that latching means of any desired form may be provided for retaining the lever 98b in operated position if it is desired to render it unnecessary to manually hold it in operative position. Lever 98b acts through the links 98d and 98g to move the levers 98 about their pivots. The levers 98 act through the bail 101d to move the ends 101c of the adding transfer levers 101 upwardly from engagement with the stops 102 on the actuator bars so that the ends 101c by engagement with stops 102 of bars 13a which do not have their bar locks released, because no key has been depressed in the corresponding column or one to the right thereof, may not act to prevent meshing of pinions 90 with toothed portions 85 during the rearward movement of released actuator bars. The ends 101b of the transfer levers are moved from engagement with the pinion cams 91a and out of the paths of movement of the raised portions 91b thereof to permit subtractive movements of pinions 90 through zero position if required.

The movement of links 98d and 98g by subtracting lever 98b also rocks bell cranks 98p. On rocking of bell cranks 98p the slides 62 are moved upwardly on pinion frames 92. The studs 62b adjacent the ends of the slides engage the arms 63a of bell cranks 63 and turn the latter to move the latch trips 92f which contact the pins 92g on the latches 92b, moving the latches out of engagement with the pinion frames 92, so that springs 92e may act to mesh the pinions 90 with toothed portions 85 for operation during the rearward movement of released actuator bars from blank to zero printing position.

The depression of numeral keys controls the actuator bars in movement as previously described; that is, actuator bars for columns in which keys have been depressed have their bar locks and zero locks released so that the bars may move the printing segments in accordance with the value of depressed keys; the bar locks for columns to the right of a depressed key are released to permit the bars to index members 84 in zero printing position, the movement of the bars being limited by their zero locks, which have not been released; and both the bar locks and the zero locks for columns to the left of the amount are maintained in locking position so that these actuator bars do not move and no figures, including zeros, will be printed in these columns.

When the operating handle is moved rearwardly, the shaft 103 turns and the cams 136 release their pawls 140 for engagement in the notches 140b of bars 138 as the latter are retracted by levers 141 to release the corresponding frames 92 in the manner described. Since the latches 92b have been released from engagement with the pinion frames by the trips 92f the springs 92a act to move the numeral pinions 90 from engagement with pinion locks 95 and into engagement with the toothed portions 85 of the printing segments.

The restoring levers 104 are carried with the shaft 103 to permit certain actuator bars to move in accordance with the values of depressed keys and others to move as far as the zero printing position.

During the movement of frames 92, but prior to meshing of pinions 90, the released actuator bars index the zero printing portion of segments 84 to the printing line. Some slight movement 10 of the frame 92 in a counterclockwise direction will result on release of the elements above described. Then, as the actuating handle is pulled forward, the main drive shaft 151 will be rotated clockwise and the bar 138 will be retracted or 15 moved forwardly by the pivoted lever 141. The frames 92 move counterclockwise with the bars 138 and the actuator bars will also move rearwardly. The early movement of the actuator bars is extremely short. This first rearward movement 20 of the released actuator bars 18 is equivalent to the displacement of only one numeral position on the printer. That is, those segmental gears 84 which are permitted to move, move only from blank to zero position before the accumulator 25 gears engage the segmental gears 84. Due to the fact that the teeth of both the segmental gears 84 and the accumulator gears 90 are large, they will mesh sufficiently accurately during the rearward movement of frame 92 to prevent any inaccuracy in the position of the accumulator gears 30 relative to the segmental gears. Thus, the teeth on the accumulator gears 90 will be disposed somewhere between the proper teeth on the segmental gears 84 and will be correctly positioned 35 when these gears come into full mesh. Upon continued forward movement of the actuating handle, the parts associated therewith will move to the positions shown in Fig. 15 and the actuator bars 18 will move rearwardly a sufficient distance 40 to properly index the segmental gears 84 and the accumulator gears 90. As the lower ends of the pinion frame 92 move forwardly the pins 92h thereon move to swing the trips 92f away from the latch pins 92g. The latches are operated by 45 their springs 92d to again engage, but not lock, the pinion frames 92. During the rearward movement of the actuator bars, as the restoring levers 104 turn with shaft 103, the printing segments 84 are moved to printing position and the numeral 50 pinions 30 are operated subtractively in accordance with the values of the keys depressed.

After the actuator bars have indexed the printing segments in printing position, platen 38 is moved against the type faces to effect printing, 55 as previously described. After printing has taken place, studs 88g carried by links 88c move toward and engage the slides 62 on the frames 92 to move the frames to carry the pinions 92 from toothed portions 85 and into engagement with pinion 60 locks 95 as is more fully described in my Patent No. 1,938,907. As the pinions 90 are demeshed the pins 92h on frames 92 permit the springs 63d to move the latch trips 92f rearwardly against pins 92g on latches 92b, which, however, are held 65 away from frames 92 by the studs 105 on the rearwardly positioned restoring frames.

After printing has occurred and the pinions 90 have been disengaged, all the bar locks for actuator bars which have not moved to or beyond zero 70 indexing position are released by stud 103c on shaft 103 acting through lever 61b as previously described, and these bars move one step rearwardly and are held by their zero locks, as previously described.

75 When the operating handle is released and

moves rearwardly, the main springs 151e act to move the restoring levers 104 forwardly. The studs 105 move away from the latches 92b which are moved by their springs 92d to engage and lock the pinion frames 92 for holding the pinions 5 90 out of engagement with the toothed portions 85 and in engagement with the pinion lock 95.

As the restoring levers 104 turn with the shaft 103 they drive the actuator bars forwardly toward normal position and restore the printing segments to position their blank portions at the printing line, but they do not effect operation of the numeral pinions 90 which are held in disengaged relation by the latches 92b.

If, during the rearward movement of the actuator bars, any of the numeral pinions 90 move from zero through the nine position (subtractively), the pinion of higher order is operated to effect the transfer by suitable mechanism such as disclosed in my Patents Nos. 1,938,907, or 20 1,957,960.

The cams 136 turn with the restoring lever shaft 103 and release the bars 138 for moving the pinion frames 92 at the end of the rearward stroke of the operating handle for further locking the numeral pinions in engagement with the pinion locks 95. The restoring levers 104 move the actuator bars to restore all of the actuator bars to their normal position. The keystem locks, released bar locks, and zero locks are actuated by the operation of cams 13a on the actuator bar or bars, and the bar locks, zero locks and depressed keys are restored to normal position, all as previously described.

At the end of the subtracting operation the 35 subtracting lever 98b is released.

On release of the subtracting lever 98b it is restored by springs 98i and operates links 98d and 98g to permit springs 98a to rock levers 98 downwardly so that the bail 101e carried by the 40 levers 98 engages the adding transfer levers 101 moving their ends 101c into engagement with the stops 102 on the actuator bars and their ends 101b into engagement with pinion cams 91. Levers 98d and 98g also turn bell cranks 98p to 45 move the slides 62 downwardly moving the studs 62b away from the arm 63a of the bell cranks 62. The bell cranks 63 are restored and the latch members 92f are again positioned by spring 63d above the pin 92g on the latches 92b. The 50 springs 92d of latches 92b restore the latches with pins 92g in contact with the ends of trip members 92f.

After a series of adding or subtracting operations have been performed, some of the numeral 55 pinions 90 have been moved to various positions. The numeral orders in which the pinions have moved away from the zero position, either by the entry of amounts through operation of keys in corresponding columns or as a result of transfer 60 operations, have their cams 91 positioned so that the raised portion 91a of cam 91 is out of engagement with the corresponding cipher lock lever 134. The springs 132 associated with these cipher lock levers turn the levers about the shaft 65 101a to maintain the upper end of the levers in contact with the cams 91 and the lower end 126 of each lever acts on the corresponding cipher lock 134 to move the latter rearwardly about the shaft 129, the force of the springs 131 associated 70 with the cipher locks 134 being overcome by the superior springs 132 associated with the cipher lock levers. Thus, certain of the cipher locks 134 have been moved rearwardly about the shaft 129 to inoperative position.

When the total key 74 is depressed the shaft 74h is turned and acts through links 74l and 74n to move the slides 62 upwardly. This upward movement of the slides 62 does not affect the lever 98b because of the pin and slot connection 62d, 62e. The pins 62b near the end of slides 62 also act on the bell cranks 63 for operating the latch tripping members 92f and releasing latches 92b to permit operation of frames 92 by springs 92a for meshing pinions 90 with toothed segments 84 during the rearward movement of the actuator bars.

It will be remembered that the total key has a lug 74g which overlaps a lug 75c on the subtotal key 75, so that depression of the total key also effects depression of the subtotal key. Consequently, when key 74 is operated the links 75f and 75h are operated through shaft 75e and act on the arms 129b on shaft 129 to move the cipher locks 134 upwardly so that their upper ends are positioned adjacent the shoulders 133 on the actuator bars. Those cipher locks corresponding to numeral pinions which have been moved from zero position have been turned about the shaft 129, as described above, so that their upper ends are positioned out of the path of movement of shoulders 133 on the corresponding actuator bars.

The cipher locks 134 for all denominations to the right of any column in which a numeral has been entered are also swung about the shaft 129 so that their ends are out of the path of the shoulders 133. This is effected by cooperative relation of the cipher locks to permit the printing of ciphers to the right of a column having a numeral therein, as disclosed in my Patent No. 1,938,907.

The movement of links 75f and 75h also causes the studs 75i to engage the arms of bell cranks 63 moving the latch tripping members 92f for releasing the latches from engaging relation with the pinion frames 92. Pins 62b on slides 62 also perform this function on depression of the total key itself. Although there is a seeming duplication of function, it may be stated that pins 62b are provided especially for effecting release of the latches on subtracting operation as previously described.

The movement of links 75f and 75g also turns bell cranks 75k raising the members 75l. Since the seats 75n at the upper ends of these members rest beneath the levers 98, the latter are turned about their pivots. As a result, the bail 101d acts to move the ends 101c of transfer levers 101 away from the stops 102 on the actuator bars so that frames 92 may move for meshing pinions 90 with members 85 although some bars 13 are locked against movement by the related cipher locks 134. The ends 101b are moved away from cams 91 but the movement of levers 98 by members 75l is not sufficient to move the ends 101b of the transfer levers from the paths of movement of the raised portions 91b of cams 91. As a result, the transfer levers 101 remain effective to serve as zero stops for pinions 90.

Depression of subtotal key 75 by total key 74 also acts through studs 75c and 75a on the subtotal key to move the bell cranks 61 and 73a (Figs. 3 and 4), so that all of the bar locks and all of the zero locks are simultaneously released to permit the actuator bars to move in accordance with the amount entered in the numeral pinions 90.

When the operating handle connected to the main shaft is moved rearwardly the restoring lever shaft 103 is turned and the cams 136 carried therewith to permit the bars 138 to be re-

tracted and latched from engagement with the pinion frames 92. The pinion frames 92 are thereupon moved by the springs 92a so that the numeral pinions 90 move from engagement with the pinion locks 95 into engagement with the toothed portions 85 of the printing segments 84. 5

As frame 92 moves the latches 135 engage those cipher locks 134 having their ends positioned in the path of shoulders 133 in order to hold the locks firmly in raised position. The latches 135 10 cannot engage the corresponding cipher locks 134 which have been moved about shaft 129 by levers 124 since either figures or zeros are to be printed in the corresponding columns.

As the frames 92 move the pins 92h swing the 15 trips 92f from engagement with pins 92g and latches 92b are operated by springs 92d to engage the frames.

When the shaft 103 turns the restoring levers 104 move therewith, permitting the actuator bars 13 to be moved rearwardly by their springs 13c. 20 As the levers 104 move and prior to engagement of pinions 90 the released bars 13 index the corresponding printers in zero printing position. This insures printing of zeros to the right of pinions 25 having figures therein.

The actuator bars 13 for columns in which numbers have been entered move rearwardly to an extent determined by the number entered in the numeral pinions, the movement of the pinions 30 and the indexing of the printing segments being limited by the engagement of the raised portion 91a of cams 91 with the ends 101b of the transfer levers 101 which act as zero stops for the pinions. The actuator bars 13 for columns to the left of 35 the amount on the numeral pinions are held against any movement as the related cipher locks 134 have their upper ends positioned in the paths of movement of and are held firmly against the shoulders 133 on these actuator bars as a result 40 of operation of the total key.

After the amount on the numeral pinions 90 has been transferred to the printing segments 84, the platen 88 is moved through links 88c against the printing segment to effect printing of the 45 total. After printing has taken place in a totalling operation the studs 88g on the links 88c engage the slides 62 and rock the pinion frames forwardly so that the pinions 90 demesh from the toothed segments 85 and engage the pinion locks 50 95, as described for subtraction. At this time the studs 105 on the restoring levers 104 prevent full upward movement of the latches 92a into engagement with the pinion frames, as in subtraction.

When the operating handle on the main shaft 55 is released and moves forwardly the studs 105 on the restoring levers 104 move away from the latches 92b, which engage the pinion frames 92 to hold the pinions demeshed during the forward movement of the actuator bars by the restoring levers 104, as in subtraction.

As the restoring levers 104 move the actuator bars 13 to normal position the racks 37 move the printing segments 84 so that the blank spaces are again presented at the printing line. Cams 136 65 release bars 138 to further lock pinions 90 engaged with their locks 95. In the final movement of the actuator bars, key stem locks, bar locks and zero locks are restored to locking relation with the actuator bars, all as previously described. The movement of the bar 29d to release the key stem locks, bar locks and zero locks also effects releasing of the key stem lock 74a for the total key and subtotal key which are restored to normal position by their springs 74b and 75b. 70 75

On restoration of the subtotal key the links 75f and 75h move the cipher locks and members 75l to normal position.

5 Springs 98a restore levers 98 and cause the ball 101e to move the ends 101b of transfer levers 101 against cams 91 and the ends 101c into engagement with the stops 102 on the bars 13.

On restoration of total key 74 the slides 62, latch trip 92f, etc., are restored to normal position on movement of the links 75l and 75n. The 10 springs 131, 132 associated with the cipher locks and the cipher lock levers also act to restore the latter to their normal position.

When the subtotal key is depressed to take a 15 subtotal, the operation is as described above, except as stated hereafter. The slides 62, being connected to the total key, but not to the subtotal key, are not moved upwardly and the studs 88g on the links 88c cannot act to demesh the numeral 20 pinions 90 from the toothed portions 85 of the sectors 84 after printing has taken place. Consequently, during the restoring operation of bars 13, the printing sectors and the adding pinions 25 are operated by the racks 37, the printing segments being restored to blank position and the 30 numeral pinions being operated to reinsert the amount in the pinions. At the end of the return stroke of the operating handle the bars 138 engage the pinions frames 92 and effect demeshing 35 of the pinions 90 from the toothed portions 85 of segments 84, as in addition.

It should be noted that the transfer mechanism disclosed herein is particularly adapted for use in conjunction with locks controlling the 35 actuator bars to inhibit the printing of ciphers to the left of the highest significant figure by preventing movement of the corresponding actuator bars and yet permitting cipher printing in columns to the right in which keys have not 40 been depressed or values registered.

As disclosed herein the restoring levers 104 45 actuate the pinion frame latches 92b, after printing has taken place, in order to unlock frames 92 for movement to mesh pinions 90 with the toothed portions of segments 84 to effect registration. The automatic release, after printing has taken place, of all previously unreleased bar locks 40 by restoring lever shaft 103 acting through lever 61b permits the actuator bars for 50 columns to the left of the highest significant figure to be moved rearwardly so that the stops 102 thereon by engagement with the locking ends 101c of transfer levers 101 may not prevent movement of frames 92 to mesh the pinions 90 in preparation for the registering operation. The rearward movement of these bars is limited to one step by their zero locks 64 as 55 in the case of bars for columns to the right of a depressed key.

60 The one step movement of the bars for columns having no depressed key also insures that all bars are positioned rearwardly so that they may have the forward movement required to effect necessary transfers.

65 The action of the locking ends 101c of the transfer levers to hold actuator bars for columns in which keys have not been depressed one step from restored position until after the 70 restoring lever shaft 103 has ceased to move the actuator bars forwardly causes the related restoring levers 104 to be held from full forward movement while shaft 103 continues to move and thus stores power in the springs 107 75 to effect delayed transfers and to restore non-

transferring bars to normal position when pinions 90 are moved forwardly.

In subtracting, totalling and subtotalling operations the pinion frames 92 should be unlatched to permit the pinions to be operated during the rearward movement of the actuator bars and therefore the subtracting lever and total keys have been disclosed as operating through latch trip 92f to immediately unlock frames 92. It should also be noted that inasmuch as the locking ends 101c of transfer levers 10 engage the bar stops 102 the subtracting lever and total keys act through levers 98 and member 75n, respectively, to raise the parts 101c so that actuator bars held in normal position 15 against movement, by their zero locks in subtraction or by the cipher locks 134 in totalling and subtotalling, do not act through bar stops 102 to prevent rearward movement of frames 92 to carry pinions 90 to operative relation with 20 printing segments 84.

It should be understood that many of the parts illustrated are shown in a form chosen purely for simplicity of illustration and to provide a complete showing of related parts and 25 do not necessarily represent preferred embodiments. For example, the mechanism for moving the platen frame to effect printing and for moving it away from the type faces after printing is illustrated only for completeness of description and may be replaced by various well known types of printing mechanisms. The frame latching mechanism for maintaining the pinions demeshed during rearward movement of the actuator bars in adding operations and during forward movement of the bars in subtraction and 30 totalling operations, together with the releasing devices therefor, is another instance in which the details of the arrangement shown should not be considered a preferred nor final form. 40

As there are many changes and variations which may be made in the form of my invention without departing from the spirit thereof, I desire to include all such variations and changes within the scope of the appended claims. 45

I claim:

1. In a calculating machine, a calculating pinion; a movable actuator bar operatively associated with said pinion to drive the latter; means for urging the bar rearwardly; a series 50 of depressible keys cooperating with said bar to limit rearward movement of said bar to one increment more than the number of increments corresponding to the value of a depressed key; a bar lock for locking said bar in normal position against movement; means actuated by the depression of any of said keys for releasing said lock to permit said bar to move rearwardly; a shaft; a restoring lever carried by said shaft and movable therewith for engaging said bar 60 to move the latter forwardly; a stop on said bar; a transfer lock for engaging said stop to limit the movement of said bar forwardly to a number of increments corresponding to the value of a depressed key; a calculating pinion 65 of lower denomination; means associated with the latter calculating pinion for releasing said transfer lock to permit said restoring lever to move said actuator bar one increment more than the incremental value of a depressed key 70 while said actuator bar is in operative relation to said first calculating pinion; and means connecting said restoring lever and said shaft for resiliently opposed relative movement therebetween whereby said restoring lever can move 75

relatively to said shaft to move said actuator bar one increment more than the incremental value of said key for effecting a transfer operation.

5. 2. In a calculating machine, a calculating pinion; a movable bar operatively associated with said pinion to drive the latter; means normally urging said bar rearwardly; a series of depressible keys cooperating with said bar for limiting rearward movement of said bar to one more increment than the number of increments corresponding to the incremental value of a depressed key; a bar lock for locking said bar in normal position against movement; means controlled by the depression of any of said keys for releasing said lock to permit said bar to move rearwardly; a shaft; a restoring lever carried by said shaft and movable therewith for engaging said bar to move the latter forwardly; a stop on said bar; and a lock for engaging said stop to limit the movement of said bar in said one direction to a number of increments corresponding to the incremental value of a depressed key.

3. In a calculating machine; a calculating pinion; a movable bar operatively associated with said pinion to drive the latter; means normally urging said bar rearwardly; a series of depressible keys cooperating with said bar for limiting the movement of said bar to one more increment than the number of increments corresponding to the incremental value of a depressed key; a bar lock for locking said bar in normal position against movement; means controlled by the depression of any of said keys for releasing said lock to permit said bar to move rearwardly; a shaft; a restoring lever carried by said shaft and movable therewith for engaging said bar to move the latter forwardly; a stop on said bar; a lock for engaging said stop to limit the movement of said bar forwardly to a number of increments corresponding to the incremental value of a depressed key; and means for moving said calculating pinion from operative relation to said actuator bar and for freeing said bar stop from its lock after said bar has moved forwardly a number of increments corresponding to the incremental value of a depressed key.

4. In a calculating machine, a calculating pinion; a movable actuator bar for operating said calculating pinion, said calculating pinion being movable into and out of operative relation to said bar; means normally urging said bar rearwardly; a series of depressible keys cooperating with said bar for limiting the movement of said bar to one more increment than the number of increments corresponding to the value of a depressed key; a bar lock for locking said bar in normal position against movement; means controlled by said keys for releasing said bar lock; a zero lock cooperating with said bar to limit the movement of said bar to one increment when a key corresponding to said bar has not been depressed; a shaft; a restoring lever carried by said shaft and movable therewith for moving said bar forwardly to normally cause operation of said calculating pinion thereby; a stop on said bar; a lock for engaging said stop to prevent forward movement of said bar by said restoring lever beyond a one increment rearward displacement while said calculating pinion is operatively associated with said bar; and a resilient connection between said restoring lever and said shaft for moving the lever relatively to said shaft to restore said bar to initial position when said calculating pinion is out of operative engagement with said bar.

5. In a calculating machine having a calculating pinion and a segmental gear member; a movable actuator bar for operating said calculating pinion and said segmental gear member, said calculating pinion being movable into and out of operative relation to said segmental gear member; means normally urging said bar rearwardly; a series of depressible keys cooperating with said bar for limiting the rearward movement thereof to one increment more than the number of increments corresponding to the value of a depressed key; a bar lock for locking said bar in normal position against movement; means actuated by said keys for releasing said bar lock; a zero lock for limiting rearward displacement of said bar to one increment from initial position to advance said segmental gear member to zero position when a key corresponding to said bar has not been depressed; a shaft; a restoring lever carried by said shaft and movable therewith for moving said bar forwardly; a stop on said bar; a transfer lock for engaging said stop to limit forward movement of said bar by said restoring lever beyond said one increment rearward displacement; a calculating pinion of lower denomination; means associated with said latter pinion for releasing said transfer lock to permit said actuator bar to move one increment while said segmental gear member operatively engages said pinion; and a resilient connection between said restoring lever and said shaft resiliently urging said lever to move relatively to said shaft and to move said bar one increment to effect a transfer from said pinion of lower denomination to said other pinion.

6. In a calculating machine having a calculating pinion and a segmental gear member; a movable actuator bar for operating said calculating pinion and said segmental gear member, said calculating pinion being movable into and out of operative relation to said member; means normally urging said bar rearwardly, a series of depressible keys cooperating with said bar for limiting the movement thereof to one increment more than the number of increments corresponding to the value of a depressed key; a bar lock for locking said bar in initial position against movement; means controlled by said keys for releasing said lock; a zero lock for limiting rearward displacement of said bar to one increment from normal position to advance said segmental gear member to zero position when a key corresponding to said bar has not been depressed; a shaft; a restoring lever carried by said shaft and movable therewith for moving said bar forwardly; a stop on said bar; and a lock for engaging said stop to limit forward movement of said bar by said restoring lever beyond a one increment rearward displacement while said calculating pinion is operatively associated with said segmental gear member so that the single increment of movement given to said bar for moving said segmental gear member to zero position does not cause operation of said calculating pinion.

7. In a calculating machine having a calculating pinion and a segmental gear member; a movable actuator bar for operating said calculating pinion and said segmental gear member, said calculating pinion being movable into and out of operative relation to said segmental gear member; means normally urging said bar rearwardly; a series of depressible keys cooperating with said bar for limiting the movement thereof; a bar lock for locking said bar in normal position against movement; means controlled by said keys for re-

leasing said lock; a zero lock for limiting rearward displacement of said bar to one increment from normal position to advance said printing member to zero position although a key corresponding to said bar has not been depressed; a shaft; a restoring lever on said shaft engageable with said bar to move the latter forwardly; a stop on said bar; a transfer lock for engaging said stop to prevent movement of said bar by 10 said restoring lever forwardly beyond said one increment rearward displacement; a calculating pinion of lower denomination; means associated with the last named pinion for releasing the transfer lock of said actuator bar when a transfer is to be effected; a resilient connection between said restoring lever and said shaft whereby the restoring lever can move said bar an increment to effect the transfer when the transfer lock is released; and means controlled by said shaft for moving the calculating pinions out of operative relation with said segmental gear member and for moving the transfer lock forwardly with the stop on said actuator when it has not been released to effect a transfer.

8. In a calculating machine, a reciprocating actuator bar, a calculating pinion, means engaging and movable by said actuator bar for rotating said pinion, means for bringing said pinion into operative engagement with said first mentioned means, a rotatable shaft extending transversely of said bar, a restoring lever mounted on said shaft and engageable with said actuator bar, means resiliently connecting said re-

storing lever to said shaft for relative resiliently opposed movement therebetween whereby the shaft may rotate without moving said actuator bar, and means responsive to the movement of said shaft for disengaging said pinion from said first mentioned means.

9. In a calculating machine; movable actuator bars having toothed portions engaging toothed segments; individual restoring levers engaging the respective actuator bars to move them forwardly to determined positions, said restoring frames having a limited relative movement with respect to each other; means for limiting the forward movement of said actuator bars to positions rearwardly of said determined positions by the respective restoring levers; means for releasing said restraining means; and resilient means interposed between said levers for effecting limited independent movement of the restoring levers to move the related actuator bars to said determined positions.

10. In a calculating machine, movable actuator bars having toothed portions engaging toothed segments, means normally urging said bars rearwardly, a shaft, individual restoring levers mounted on the said shaft for engaging the respective bars to move the latter forwardly, accumulating means movable into and out of engagement with said toothed segments, and means responsive to movement of said shaft for moving said accumulating means into and out of engagement with said toothed segments.

FRANCIS A. HOSACK.
